UNITED STATES PATENT OFFICE.

THEODORE A. WILLARD, OF CLEVELAND, OHIO, ASSIGNOR TO THE WILLARD STORAGE BATTERY COMPANY, A CORPORATION OF OHIO.

TERMINAL FOR BATTERY-PLATES.

1,050,893.

Specification of Letters Patent. Patented Jan. 21, 1913.

Application filed April 1, 1909. Serial No. 437,353.

To all whom it may concern:

Be it known that I, THEODORE A. WILLARD, a citizen of the United States, residing at Cleveland, in the county of Cuyahoga and State of Ohio, have invented a certain new and useful Improvement in Terminals for Battery-Plates, of which the following is a full, clear, and exact description.

10 The present invention relates to terminal posts for battery plates, and more particularly is directed to the provision of a novel exterior surface for the terminal post.

15 The object of the invention has been to provide means for preventing the creeping of the battery solution over the terminal post to the connecting wire.

20 It has long been known that one of the most objectionable defects of storage batteries has been the tendency of the battery solution, whether it be acid or alkaline, to creep up the post, and numerous expedients have been tried for preventing this action.

25 The object of the present invention has been to eliminate the possibility of such an occurrence in the most effective manner and to achieve this end by a simple means which does not call for the employment or advice of an expert after the battery has been 30 placed in the user's hands.

35 The above object will be seen to be attained by that embodiment of my invention described in the following specification with reference to the accompanying drawings, in

40 Figure 1 is a transverse section through a storage battery showing plates with terminals constructed in accordance with my improvement. Fig. 2 is a vertical transverse section through one of the terminals shown in Fig. 1. Fig. 3 is also a vertical section through a terminal of slightly different construction so far as the device for securing the connecting wire is concerned. Fig. 4 is 45 a side elevation of still another form of terminal, also provided with my improvement.

50 I have determined the fact that if I provide the terminal posts A, in a zone above the battery solution, with an exterior coating or covering B of vulcanized rubber or similar inert material, so held and united to the terminal post that there are no loose joints or crevices through which the solution 55 may creep in between the rubber and the

metal of the post, that, although the solution may creep up the terminal to the zone where the rubber is placed, it will not pass beyond. The construction which I prefer to use is that of a terminal post capable of being secured in the ordinary manner to the battery plates and having a reduced neck A' with a shoulder A² at each end, about which neck may be placed soft rubber, which is afterward vulcanized. Preferably, 35 I serrate the surface of the neck of the post as at A³ for the purpose of affording a greater surface of contact between the soft rubber and the neck and binding the two together more firmly, so as to avoid all looseness of fit. After vulcanization, it will be found that the smooth rubber coating or covering fits tightly in the position into which it has been pressed, and, owing to its being hardened, quite capable of taking a 70 thread wherever the modification of terminal post is such as to require it, as, for example, in that form shown in Fig. 3. There are, of course, other materials which are the equivalent of rubber in this connection, 75 but there are obvious advantages in using rubber which lead me to use it as the preferable material, but it is essential that the covering sleeve, whatever it be, be not subject to oxidation or sealing by the battery 80 solution, whether the latter be acid or alkaline. If any substance be used which can be oxidized or scaled by the solution, or which may already have a rough surface like that formed in oxidation, it will prove ineffective 85 as the ordinary plain metallic terminal post.

90 In the construction shown in Fig. 2 the terminal has a transverse opening C adapted to receive a connecting wire which may be clamped in position by a binding screw D. In the modification shown in Fig. 3 the terminal has a transverse opening C for the connecting wire which may be clamped securely in position by means of an internally threaded cap E which may be screwed onto the upper end of the rubber layer B. In the modification shown in Fig. 4 the terminal has at its upper end an eye F provided with an opening adapted to receive a screw or other member for securing the connection between the battery plate and wire.

95 It will be seen by the above construction that I have attained the object of invention indicated.

Having described my invention, I claim:

The combination in a storage battery, a battery plate, a casing inclosing the plate and adapted to contain battery solution, a 5 cover for the casing, and a terminal post for the plate extending upwardly through the cover, said post comprising a metallic body having means for preventing creepage of battery solution along the post above said 10 cover to the point of connection of a con-

necting wire, the said means for preventing creepage comprising a layer of rubber vulcanized directly to said metallic body.

In testimony whereof, I hereunto affix my signature in the presence of two witnesses. 15

THEODORE A. WILLARD.
